Des. 62,564

UNITED STATES PATENT OFFICE.

FREDERICK A. COADY, OF LONG BEACH, CALIFORNIA.

DESIGN FOR A TABLE.

Application filed March 4, 1922. Serial No. 1,030. Term of patent 7 years.

To all whom it may concern:

Be it known that I, FREDERICK A. COADY, a citizen of the United States, residing at Long Beach, in the county of Los Angeles and State of California, have invented a new, original, and ornamental Design for a Table, of which the following is a specification, reference being had to the accompanying drawing, forming part thereof.

Fig. 1 is an end view of the table showing my new design, the leaves raised, and

Fig. 2 a side view of same.

I claim:

The ornamental design for a table, as shown.

FREDERICK A. COADY.

Witnesses:

BLANCHE COADY,
LOUIS J. KROPP.
